OVERHEAD CONVEYER SYSTEM

Frank C. Harris, Lakewood, Ohio, assignor to
The American MonoRail Company, Cleveland,
Ohio, a corporation of Ohio

Application December 23, 1938, Serial No. 247,420

3 Claims. (Cl. 191—32)

This invention relates to electrified overhead conveyor systems and more particularly to insulators or supports for the conductor bars of such systems.

In the electrification of overhead rail runways it is desirable to have the conductors which extend along the overhead track arranged as compactly as possible. A compact arrangement of conductors lessens the expense of construction and installation, the possibility of contact with the conductors by materials being handled on the floor below is practically eliminated, and the cost of switches and the space required by switches is greatly reduced as compared to a system embodying trolley wires extending along the rail because of the fact that the throw or shift of the switches in compact systems is reduced to less than half the throw or shift required with trolley wire systems of the same capacity.

For the above reasons, among others, electrified overhead rail runways embodying closely spaced relatively rigid conductor bars are very advantageous and it is an object of my invention to provide a simple and economical form of insulator for supporting such conductor bars along an overhead track or crane runway. Another object of my invention is to provide such an insulator in which the leakage distances along the surfaces of the insulator are increased without increasing the spacing of the conductors, whereby the insulator can be made very compact without danger of leakage taking place. Another object is to provide an insulator adapted to support one or more conductors along a track or runway. Further objects and advantages of my invention will become apparent from the following description thereof, reference being made to the accompanying drawing. The essential characteristics are summarized in the claims.

In the drawing, Figure 1 is a vertical section through a section of overhead track showing an insulator made according to my invention secured thereto and supporting four rigid conductor bars shown in Figure 1, the line 1—1 on Figure 2 illustrating the section on which Figure 1 was taken; Figure 3 is a plan view partly in section showing one part of my insulator; Figure 4 is a similar plan view showing another part thereof.

As shown in the drawing my invention may be applied to the electrification of overhead conveyor systems embodying, for example, a track indicated generally at 10 and having flanges 11 and 12 for supporting the wheels of a trolley (not shown), a vertical web 13 and an upper flange 14. In the system illustrated there are four conductor bars

15 extending longitudinally of the track 10 on either side thereof. Of course, a greater or smaller number of conductor bars may be employed depending upon the requirements of the system, but I have illustrated four as constituting a typical installation adapted particularly for three phase alternating current, the fourth conductor being employed for a control circuit.

The conductors, which are channel shaped in cross section, are supported by insulators comprising outer members indicated generally at 20 and inner members indicated generally at 21. The members 20 are provided with longitudinally extending recesses or grooves having inner walls 22 and 23 disposed substantially at right angles 15 to each other and adapted to engage the outer surfaces of the flanges 24 and webs 25 of the respective conductor bars.

The conductor bars are retained in position by the inner members 21 which are provided with 20 longitudinally extending surfaces 26 and 27 adapted to engage the inner surfaces of the flanges 24 and webs 25 of the conductor bars. The members 20 are provided with slightly tapered recesses 30 which receive the projections 25 or sleeves 31 on the members 21 thus holding the two members in proper relationship. A passage-way 32 is provided through each of the projections 31 to receive the bolts 33 which function to clamp the inner and outer members together and 30 also to retain the insulator assembly in position on the web 13, the bolt passing through an opening 35 of the web and clamping the projecting bosses 36 of the outer members 20 against the opposed lateral surfaces of the web.

In order to prevent leakage of current from one conductor bar to another or to the bolt 33 or web 13, the parts of the insulators are shaped to provide extended paths over the surfaces thereof, thus increasing the leakage distances 40 and reducing the possibility of leakage taking place due to moisture or dirt accumulating on the surfaces of the parts of the insulator. To this end the recesses 30 and projections 31 have been extended within the bosses 36 in order that the 45 path along the contacting surfaces of the parts of the insulators from the conductors to the bolt 33 will be as long as possible. For the same purpose, the inner members 21 are counter-sunk as at 40 to receive the heads 41 of the bolts, and 50 the nuts 42. Also the inner members 21 are provided with annular projections 44 surrounding the counter-sunk openings in order to further increase the leakage distance on the exterior surface of the insulators between the conductor bars 55

and the bolt. The bosses 36 and the external surfaces 45 of the outer members 20 provide a large leakage distance on the surface of the insulators between the various conductors and the web 13.

The parts making up my insulator can be readily molded of insulating materials such as condensation products of phenol which have high dielectric strength and ample mechanical strength 10 to withstand any forces involved. The design requires only two insulating members, identical parts being employed on opposite sides of the web. Of course, if only two conductors are employed they can be spaced on the same side of 15 the web requiring only one set of parts instead of the pairs of parts illustrated in the drawing. The insulators also will function to support only one conductor bar on one side of the web, as a single conductor bar can be effectively clamped 20 between the inner and the outer members, the engagement between the projections 31 and the recesses 30 insuring proper positioning of the members 20 and 21 to securely clamp a single conductor bar. Also, if it is desired to mount 25 more than two conductors on the same side of the track, two or more of my insulators can be disposed one above the other on the track, or may be supported on brackets extending outwardly from the track.

30 Insulators made according to my invention can be readily installed and because of the design of my insulators very compact electrification systems can be employed with close spacing of the conductor bars without danger of leakage of 35 current. Thus electrified overhead rail runway systems embodying my insulators can be constructed at low cost because of the ease of installing the insulators and because the insulators permit the design and construction of compact 40 systems.

In the foregoing specification I have described in detail a preferred form of my invention. Various changes and modifications therein will be evident to those skilled in the art. It is, therefore, to be understood that my invention is not limited to the specific embodiment described herein or in any manner other than by the scope of the appended claims.

I claim:

50 1. In combination, in an overhead conveyer system, a track having lower flanges adapted to support a trolley thereon and a central web portion, rigid conductors extending along said track on opposite sides of said web portion, and insulating means for supporting said conductors comprising a pair of outer members each grooved to receive a pair of conductors, said members be-

ing disposed on opposite sides of said web portion, a pair of inner members fitting within said outer members and arranged to retain said conductors therein, two longitudinally spaced bolts disposed between said pairs of conductors and 5 extending through coaxial openings in said inner and outer members and through said web portion to clamp said members together and against said web portion, the openings through said inner members being countersunk and said 10 inner members each being provided with hollow sleeves surrounding said bolts and extending within recesses in said outer members to increase the leakage distances between said conductors and said bolts. 15

2. In combination, in an overhead conveyer system, a track having lower flanges adapted to support a trolley thereon and a central web portion, rigid channel section conductors each having a pair of flanges and a web extending 20 along said track on opposite sides of said web portion, and insulating means for supporting said conductors comprising a pair of outer members each grooved to receive a pair of conductors and to engage the outer surfaces of one flange and one web of each bar, said members being disposed on opposite sides of said web portion, a pair of inner members fitting within said outer members and arranged to retain said conductors therein, a bolt extending through coaxial 25 openings in said inner and outer members and through said web portion to clamp said members together and against said web portion, said inner members being provided with hollow sleeves surrounding said bolt and extending away from 30 said conductors within recesses in said outer members to increase the leakage distance between 35 said conductors and said bolt.

3. In combination, in an overhead conveyer system, a track having lower flanges adapted to support a trolley thereon and a central web portion, a rigid conductor extending along said track, and insulating means for supporting said conductor comprising an outer member grooved to receive said conductor, an inner member fitting within said outer member and arranged to retain said conductor therein, a bolt extending through coaxial openings in said inner and outer members and through said web portion to clamp 40 and support said members, said inner member being provided with a hollow sleeve surrounding said bolt and extending away from said conductor within a recess in said outer member to increase 45 the leakage distance between said conductor and said bolt. 50
